UNITED STATES PATENT OFFICE.

EDWARD C. LUCKE, OF LE MARS, IOWA.

SELF-SUPPORTING EXTENSION LADDER.

Application filed December 20, 1921. Serial No. 523,749.

To all whom it may concern:

Be it known that I, EDWARD C. LUCKE, a citizen of the United States, and a resident of Le Mars, in the county of Plymouth and

5 State of Iowa, have invented a certain new and useful Self-Supporting Extension Ladder, of which the following is a specification.

The object of my invention is to provide 10 a self supporting extensible ladder of simple, durable and inexpensive construction having its adjustable member so arranged that it may be easily and quickly manipulated.

15 A further object is to provide in a self supporting extensible ladder having a vertically adjustable member, improved means for supporting and locking the said adjustable member in a number of its positions of 20 movement.

These and other objects will be apparent to those skilled in the art.

My invention consists in the construction, arrangement and combination of the various 25 parts of the device, whereby the objects contemplated are attained, as hereinafter more fully set forth, pointed out in my claim, and illustrated in the accompanying drawings, in which:

30 Figure 1 is an isometrical view of my improved ladder showing the manner in which it is set up when in use.

Figure 2 is a detail side elevation of a portion of the ladder showing the manner in which it may be folded when not in use.

35 Figure 3 is a detail sectional view of a portion of the ladder showing the manner in which the adjustable member is supported between the supporting members.

40 Figure 4 is a detail sectional view of the same showing the adjustable member being moved upwardly to a new position.

45 My extensible ladder comprises a pair of supporting members 10 having side rails 11 and rungs 12. These members 10 are similar in size and shape and may be of any length desired, and are for the primary purpose of supporting a vertically adjustable member 13, which I shall term an adjustable member.

50 This adjustable member is of the same width as the supporting members and is designed to be mounted in a vertical position when in use, while the supporting members

55 10 are arranged in oppositely inclined positions with the upper ends of their side rails

11 resting adjacent to the edges of the side rails of the adjustable members. The upper ends of the members 10 are beveled at 14 so that the said beveled portions will fit 60 the edges of said extensible member.

The upper ends of the members 10 are pivotally secured to each other by means of inverted L-shaped plates 15. These plates 15 are secured to the side members 11 by 65 means of bolts 16 and are mounted in such a manner that the angular portions 17 are pivotally connected to each other by means of a pivot 18 substantially midway between the beveled portions 14. This pivot member is 70 located in a line substantially even with the lower edges of the beveled portions 14 so that any downward movement of the member 13 by frictionally engaging the beveled portions 14 will cause said beveled portions 75 to grip the adjustable member.

Each end of the top rung 19 of one of the members 10 is provided with a pivotally mounted brace bar 20. The free ends of the bars 20 are each provided with a hook portion 21 designed to rest over the top rung 22 of the opposite member 10, as clearly shown in Figures 1 and 3.

The central and upper edge of each of the bars 20 is provided with a notch 23 so 85 shaped as to fit the bottom side of the rungs of the adjustable member in such a manner that the adjustable member may be held against downward movement by having one of its rungs resting in the notch 23, as 90 clearly shown in Figure 3.

The notch 23 is of such a depth that the downwardly extending portion of the adjustable member will be held against movement toward or from the members 10 when 95 one of its rungs rests in said notch. The brace bar 20 therefore performs two functions, one to prevent downward movement of the adjustable member, and the other to prevent swinging movement of its free ends. 100

The brace bar 20 is so arranged that as the adjustable member is moved upwardly in a vertical plane, the rung below the one which had rested in the notch 23 will engage the lower edge of the brace 20, as clearly 105 shown in Figure 4, and will cause the said brace to be elevated and successively swung out of the way of each of the upwardly moving rungs.

When the adjustable member has been 110 moved upwardly to the desired distance, the brace 20 will fall back into a horizontal posi-

tion, after which the adjustable member may be lowered a slight distance until the rung above the brace engages the notch 23. The adjustable member is thereby easily and quickly adjusted to its new position, and will be firmly and reliably held.

When it is desired to fold the ladder, the adjustable member is moved upwardly a slight distance, after which the braces 20 are swung upwardly to a position substantially as shown in dotted lines in Figure 4, after which the adjustable member may be lowered until its lower end engages the floor. The lower ends of the members 10 may then be moved toward each other until all three members of the ladder are parallel and adjacent, as shown in Figure 2. This provides means whereby the ladder may be quickly folded to a minimum amount of space.

20 Thus it will be seen that I have provided a self supporting extensible ladder of simple, durable and inexpensive construction, the adjustable member of which may be easily and quickly set in any desired working position within the range of the ladder, and which may also be easily and quickly folded to its most compact form, and one in which, when it is set up for operation will rigidly support the extensible member.

30 I claim as my invention:

An improved self supporting extension ladder comprising two supporting members, each formed of two side rails and connecting rungs, two hinges connecting their upper

35 end portions, each hinge being fixed to the outer surface of the rails and extended inwardly and having its pivotal point between the rails, said parts being so shaped that when the supporting members are inclined upwardly and toward each other, the 40 upper ends of the rails will be parallel and spaced apart, an adjustable member formed of two side rails and a number of rungs, the side rails being slidingly mounted between the side rails of the supporting members, and said parts being so shaped and arranged that when the supporting members are spread the side rails above the hinges will grip the side rails of the adjustable member, and two combined supporting and bracing bars, each being formed of a single piece of metal having a round opening at one end to receive one of the rungs of one of the supporting members and be pivotally supported thereby, the other end being formed with a notch on its under surface to receive one of the rungs of the opposite supporting member and the upper central portion being formed with a notch to receive one of the rungs of the adjustable member, and whereby the adjustable member is held against downward movement, and both of the supporting members and the adjustable member are braced against lateral movement relative to each other.

65 Des Moines, Iowa, November 22, 1921.

EDWARD C. LUCKE.
